US00D857707S

(12) **United States Design Patent** (10) **Patent No.:** **US D857,707 S**
Kennerly et al. (45) **Date of Patent:** **** Aug. 27, 2019**

(54) **DISPLAY SCREEN OF A COMPUTER WITH A GRAPHICAL USER INTERFACE WITH OBJECT TRACKING GAME**

(71) Applicant: **LUMOS LABS, INC.**, San Francisco, CA (US)

(72) Inventors: **David Ethan Kennerly**, San Francisco, CA (US); **Benjamin Lee Ahroni**, San Francisco, CA (US); **Aaron Kaluszka**, Hayward, CA (US)

(73) Assignee: **LUMOS LABS, INC.**, San Francisco, CA (US)

(**) Term: **15 Years**

(21) Appl. No.: **29/588,353**

(22) Filed: **Dec. 20, 2016**

Related U.S. Application Data

(63) Continuation of application No. 14/338,165, filed on Jul. 22, 2014, now abandoned.

CLAIM

The ornamental design for a display screen of a computer with a graphical user interface with object tracking game, as shown and described.

DESCRIPTION

The FIGURE is a front view of a display screen of a computer with a graphical user interface with object tracking game.

The broken line showing of a display screen with a graphical user interface is included for the purpose of showing portions of the article which forms no part of the claims.
